UNITED STATES PATENT OFFICE.

WILLIAM A. MACDONALD, OF HARTSDALE, NEW YORK.

MODULATION.

Application filed November 12, 1920. Serial No. 423,536.

To all whom it may concern:

Be it known that I, WILLIAM A. MACDONALD, a citizen of the United States, residing at Hartsdale, in the county of Westchester, State of New York, have invented certain new and useful Improvements in Modulation; and I do hereby declare the following to be a full, clear, and exact description of the invention, such as will enable others skilled in the art to which it appertains to make and use the same.

This invention has for its object the provision of an improved method and apparatus for obtaining unusually effective and efficient modulation of the carrier frequency electrical oscillations in a wave signalling system without producing variations in the frequency of the carrier wave.

The particular advantages gained, as well as the difficulties overcome, by the present invention, will be understood from the following explanation: At the present time, three general methods of controlling or modulating high frequency oscillations are in general use, namely, so-called absorption methods, grid control and plate control. Of the absorption methods the most common are the varying of the amplitude of low power high frequency oscillations or carrier frequency, by a microphone inserted in the output line or radiating circuit, according to whether a so-called "wired-wireless" system or radio signaling system is employed. For higher powers, the absorption of the unmodulated antenna or output current is generally effected by an appropriate number of vacuum tubes or valves.

Grid modulation has been employed to some extent but with only fair success because of its inherent inefficiency. It is accomplished in the case of telephony, for example, by inserting a microphone and an audio frequency or speech transformer in the grid circuit of a three-element valve. When speech is impressed on the microphone, the potential of the grid is thrown either positive or negative with respect to its normal potential, thereby varying the load on the plate and consequently the output of the tube.

The circuit arrangement employed with plate control or modulation is generally referred to as the constant current system. In this system one or more tubes are used as

oscillators and a suitable number as modulators. When the grid voltage of a modulator tube is varied, for example, by means of a microphone, the resistance is varied between infinity and almost zero, thereby making available for the oscillator twice the voltage when the resistance of the modulator is infinity and practically nothing when the resistance falls almost to zero. The effectiveness of constant current modulation depends to a great extent upon the presence and character of a suitable choke in the circuit, but good modulation will not be effected if the modulator tube does not have ample electron emission from the filament.

All of the above-mentioned methods of control are limited by the difficulty of maintaining the carrier frequency constant, since the modulation in each case will cause variations of the frequency of the oscillations generated by the oscillator. Moreover, it is a well known fact that in continuous or undamped wave signaling systems where the signal is received by virtue of the difference of the incoming frequency and the frequency of a local source of oscillations, any slight change in the transmitted frequency and hence in the incoming energy will cause perceptible and objectionable changes in the received note, in many cases a total loss of signal. This, of course, is less pronounced in radio telephony or buzzer-modulated radio telegraphy, but it is a very objectionable feature.

It has heretofore been proposed to use an oscillator whose output is modulated in accordance with the desired signal or with speech in the case of telephony, and to amplify the resulting modulated oscillations by means of a power amplifier. This arrangement, however, is characterized by troublesome variations in the frequency of the amplified modulated-oscillations produced as a result of the modulation of the oscillator, as explained above.

A solution for the troublesome variations in the carrier frequency produced by modulation lies in the use of a so-called master oscillator or frequency-setter, the frequency of the oscillations which are produced thereby being incapable of variation regardless of its association with suitable modulating means. To this end and in accordance with the present invention, a method and appa-

2
 ratus is provided wherein a master oscillator or frequency setter is employed whose frequency of oscillation is unvaried by the action of the modulating means. A convenient manner of obtaining a source of constant frequency controllable high frequency supply lies in the use of a regenerative vacuum tube oscillator associated in a suitable manner with the input side of a vacuum tube power amplifier, the oscillations being preferably impressed upon the grid or grids of the vacuum amplifier. A suitable number of modulating tubes may then be associated with the power amplifier and arranged to modulate its constant frequency output by operating on the output circuit or plates of the amplifying tubes. The modulator in this case cannot vary or change the frequency of the amplified oscillations, and for reasons which can be easily shown by demonstrable experimental facts, superior modulation of the constant frequency carrier wave is obtained. With this arrangement, particularly in radio telephony, practically perfect speech with effective and efficient modulation of the constant frequency carrier wave is readily obtainable.

Circuit arrangements which may be used for the purpose of carrying out the invention, as well as further features and advantages thereof will be understood from the accompanying drawings and the following detail description.

I these drawings:
 35 Fig. 1 illustrates a diagrammatic circuit arrangement embodying the invention and capable of being operated in accordance with my improved method of control; and

30 Fig. 2 illustrates a vacuum tube system 40 which operates in accordance with the invention.

Referring now to Fig. 1, a master oscillator or frequency-setter 1 is arranged in the circuit 2, 3 so as to impress oscillations of the desired frequency upon the power amplifier 4. In this way the oscillations generated by the master oscillator may be amplified to any desired value or amplitude. The resulting amplified oscillations in the output circuit 5, 6 may then be controlled or modulated by the vacuum tube modulator 7, for example, in accordance with speech impressed on the microphone 8. Other forms of audio frequency modulation may be used 55 as will be understood, for example, the use of the buzzer is well known.

The frequency of the oscillations of the carrier wave having been set by the master oscillator 1, the modulated signaling energy will be radiated at a constant frequency from the antenna 9 even if variations occur in the electrical constants of the antenna circuit 9, 10. Variations of the electrical constants of the antenna circuit will, however, affect the value of the antenna current,

and therefore the amplitude of the carrier wave, but not its frequency.

The presence of a suitable choke coil 11, or band filter located in the positive lead of the high voltage input to the amplifier and 70 modulator tube or tubes, is essential to the efficient operation of the system. In any event, this choke should present a high impedance with relation to the impedance of the tube or tubes for voice frequencies. 75

In Fig. 2 a vacuum tube regenerative oscillator 12 is provided as a convenient controllable source of high frequency oscillations. The output circuit 13-14 of the master oscillator or frequency-setter 12 is 80 associated with the input or grid circuit 15-16 of the vacuum tube amplifier 17. The tube 18 modulates the output of the amplifier by variably diverting the current supply of its plate circuit, 19-20, in accordance with the known method of constant current modulation. Moreover, because of the fact that the constants of the master oscillator are not affected by variations in the amplifier circuit or antenna, carrier oscillations of continuous frequency may be generated and the frequency maintained constant throughout the entire radiating or other transmission portion of the system.

With this system and in accordance with 95 the present invention, the carrier wave may be modulated in accordance with any source of audio frequency oscillations by impressing upon the grid circuit 21-22 audio frequency oscillations in accordance with the desired signal, for example, in accordance with speech by means of the microphone 23. It is to be understood, however, that other known audio frequency devices may be substituted for the microphone. In any case, 100 the transmitted signal energy will be radiated by the antenna system 24-25 and any variations in the electrical constants of this system, will affect only the amplitude of the carrier wave but not its frequency. 110

As in the case of Fig. 1, a suitable choke coil 26, or band filter is located in the positive lead of the high voltage input to the amplifier or modulator tube or tubes.

It is to be understood that while certain 115 embodiments of the invention have been illustrated and described herein, that the various arrangements of circuits and component parts thereof may be varied without departing from the spirit and scope of this invention. 120

I claim:—

1. In a wave signaling system, means for generating continuous high frequency carrier oscillations, and amplifier for amplifying said carrier oscillations, a source of unidirectional voltage for said amplifier, a variable impedance in series in a direct current circuit with said source of voltage, means 125 for keeping the current from said source 130

substantially constant, and means for varying said impedance in accordance with signals.

2. In a wave signaling system, a generator of high frequency oscillations having an output circuit, a vacuum tube amplifier for amplifying said high frequency oscillations, said amplifier having an input circuit and an output circuit, said input circuit being associated with the said output circuit of said generator, a source of current in the output circuit of said amplifier, a variable resistance in shunt to said source of current, and means for varying said resistance in accordance with signals.

3. In a wave signaling system, a generator of continuous high frequency oscillations of constant amplitude, an output circuit for said generator, a vacuum tube amplifier having input electrodes and output electrodes, an input circuit for said amplifier, said input circuit being associated with the output circuit of said generator, an output circuit for said amplifier including said output electrodes, a load circuit associated with said output circuit, a source of uni-directional current included in the output circuit of said amplifier, an inductance coil in series with said source of current and included in said output circuit said coil being operable to maintain the flow of current from said source substantially constant, a second vacuum tube comprising a plate, a grid and

a filament, said plate and filament being connected in series with said source of current and said inductance coil and in shunt to the output electrodes of said amplifier, an input circuit for said second vacuum tube and a microphone associated with said last mentioned input circuit and operable to vary the impedance between the plate and filament of said second vacuum tube in accordance with signals to be transmitted, the arrangement being such that continuous high frequency oscillations from said generator are amplified by said amplifier and simultaneously modulated by diversion of current from said amplifier in accordance with signals impressed on said microphone and furthermore that the frequency of said oscillations is substantially unaffected by variations in the constants of said load circuit.

4. The method of producing signal modulated high frequency carrier current of substantially uniform frequency which consists in generating unmodulated high frequency carrier current of substantially constant frequency, impressing said unmodulated carrier current upon the input circuit of an amplifier, supplying current of substantially constant value to the output circuit of said amplifier and variably diverting said current away from said amplifier in accordance with signals to be transmitted.

In testimony whereof I affix my signature.
WILLIAM A. MACDONALD.

substantially constant, and means for varying said impedance in accordance with signals.

2. In a wave signaling system, a generator of high frequency oscillations having an output circuit, a vacuum tube amplifier for amplifying said high frequency oscillations, said amplifier having an input circuit and an output circuit, said input circuit being associated with the said output circuit of said generator, a source of current in the output circuit of said amplifier, a variable resistance in shunt to said source of current, and means for varying said resistance in accordance with signals.

3. In a wave signaling system, a generator of continuous high frequency oscillations of constant amplitude, an output circuit for said generator, a vacuum tube amplifier having input electrodes and output electrodes, an input circuit for said amplifier, said input circuit being associated with the output circuit of said generator, an output circuit for said amplifier including said output electrodes, a load circuit associated with said output circuit, a source of uni-directional current included in the output circuit of said amplifier, an inductance coil in series with said source of current and included in said output circuit said coil being operable to maintain the flow of current from said source substantially constant, a second vacuum tube comprising a plate, a grid and

a filament, said plate and filament being connected in series with said source of current and said inductance coil and in shunt to the output electrodes of said amplifier, an input circuit for said second vacuum tube and a microphone associated with said last mentioned input circuit and operable to vary the impedance between the plate and filament of said second vacuum tube in accordance with signals to be transmitted, the arrangement being such that continuous high frequency oscillations from said generator are amplified by said amplifier and simultaneously modulated by diversion of current from said amplifier in accordance with signals impressed on said microphone and furthermore that the frequency of said oscillations is substantially unaffected by variations in the constants of said load circuit.

4. The method of producing signal modulated high frequency carrier current of substantially uniform frequency which consists in generating unmodulated high frequency carrier current of substantially constant frequency, impressing said unmodulated carrier current upon the input circuit of an amplifier, supplying current of substantially constant value to the output circuit of said amplifier and variably diverting said current away from said amplifier in accordance with signals to be transmitted.

In testimony whereof I affix my signature.
WILLIAM A. MACDONALD.

DISCLAIMER.

1,533,653.—William A. MacDonald, Hartsdale, N. Y. MODULATION. Patent dated April 14, 1925. Disclaimer filed May 28, 1926, by the patentee.

Hereby enters this disclaimer to claims 1, 2, 3, and 4 of said Letters Patent, viz.:

He disclaims from claims 1, 2, and 3 any generator or means for generating continuous high-frequency carrier oscillations "except a vacuum tube system generator producing continuous high frequency oscillations of substantially constant amplitude and frequency, whereby such oscillations are supplied unmodulated to the modulating amplifier;" and

He disclaims from claim 4 any method of producing signal-modulated high-frequency carrier current of substantially uniform frequency "excepting where the results obtained are the results obtained by the use of a vacuum tube system generator producing continuous high frequency oscillations of substantially constant amplitude and frequency."

[Official Gazette June 15, 1926.]

DISCLAIMER.

1,533,653.—*William A. MacDonald*, Hartsdale, N. Y. **MODULATION.** Patent dated April 14, 1925. Disclaimer filed May 28, 1926, by the patentee.

Hereby enters this disclaimer to claims 1, 2, 3, and 4 of said Letters Patent, viz.: He disclaims from claims 1, 2, and 3 any generator or means for generating continuous high-frequency carrier oscillations "except a vacuum tube system generator producing continuous high frequency oscillations of substantially constant amplitude and frequency, whereby such oscillations are supplied unmodulated to the modulating amplifier;" and

He disclaims from claim 4 any method of producing signal-modulated high-frequency carrier current of substantially uniform frequency "excepting where the results obtained are the results obtained by the use of a vacuum tube system generator producing continuous high frequency oscillations of substantially constant amplitude and frequency."
